the vertical frame members 22, the outer ends of the arms being connected by pivot pins 58 to a common plate 59.

The plate members 59 carry supporting means which provides horizontal movement of the cradle, the means here shown comprising another set of parallel arms 60, 61 which are supported on the plates 59 by pivot pins 58 (lower), 62 and which support the base 24 of the cradle by pivot pins 63.

Suitable rigidifying transverse bracing is provided between the sets of parallel arms and the parallel connecting plates to hold all parts against twisting in order that true cuts may be made, the means here shown comprising channel members welded on, such as 65, 66, 67, etc., as many being used as needed.

Means are provided for balancing the workpiece supporting means and for taking into account the shifting horizontal positions of the workpiece and cradle. As shown, a primary or static adjustable balance weight 68 is threaded on a generally horizontal screw rod 69 secured to a cross bar 70 connected to the rearwardly projecting end extensions 56a of the lower arms 56 of the first or horizontal set of parallel arms. The weight 68 can be locked in adjusted positions on the rod 69 by nuts 71.

A secondary or dynamic balance weight 72 is threaded on a generally vertical screw rod 73 secured to a box-like transverse hollow beam structure 74 connected to the arm extensions 56a by pivot pins 75. A vertical bar or arm 76 is secured to the beam structure at its mid-length and extends downward for a distance equal to the length of the vertical parallel arms 60, 61.

A weight shifting connecting rod 78 is connected at its rear end to the lower end of arm 76 by a pivot pin 79 and is connected at its front end to a bracket 80 secured to the transverse beam 65 by a pivot pin 81. The pin 81 has its axis aligned with the axis of the lower rear pivot pins 63 so that the connecting rod 78 is parallel with the arm 56 and its rear extension 56a.

The arms 60 and 76 are parallel so that a parallelogram is thus formed with pivots 75, 79, 80 and 58 (lower) at the corners. The secondary weight 72, of course, partly balances the load carrying mechanism statically but its weight is so chosen and the relative values and adjustments of the two weights are so chosen that the movement of the secondary weight 72 practically balances the horizontal movements of the cradle and its load; while adjustments of the position of the primary weight 68 largely compensate for differences in weight of different workpieces which are loaded on the cradle.

By the described arrangement the shifting of the cradle and workpiece is made with little effort and there is little change in the amount of effort required at different locations of the cradle and workpiece. This is very important in the procedure of feeding the workpiece by a pattern or templet, next to be described.

FIG. 4, as stated, shows in broken lines, the outlines of the forms to be cut in the workpiece slab by the wire band saws. A templet 83 for forming this design is shown in FIGS. 6 and 7. It is shown as being secured in a frame 84, as by screws 85, and the frame 84 is secured in a fixed position on the main frame, as on horizontal bars 86, 87 attached to the vertical members 22 by any suitable means. The templet is inverted and reversed relative to the articles cut because the saw cut opposite to the direction in which the workpiece is moved.

The templet or pattern 83 shown in FIGS. 6 and 7 is of the outside periphery guiding type and is adapted to be followed by a tracing pin 88 carried on a rod 89 secured to the upper end of a guide arm 90 which, at its lower end, is rigidly secured, as by a fitting 91, to the base 24 of the cradle. A handle 92 is secured to the outer end of the rod 89. The rod is threaded and may be adjusted in and out and locked in desired position, as by locknuts 93, to place the end of the tracing pin in proper position relative to the templet.

The templet alone would not confine the tracing pin (and the saw range in the slab) to proper bounds, so, for an outside guide type of templet an auxiliary border confining templet 94 is provided for limiting the outer range 5 of movement of the tracing pin. A notch 95 is provided at the top of the border templet to allow the cradle to rise until the top spans of the saws are in the top spaces of the transverse channel members 28. The notch 95 is of such depth that the saws cannot engage any part of the channel members.

10 For greater assurance, the workpiece supporting mechanism may be provided with suitable stops to keep the saws within their proper field of action, but these stops have not been illustrated herein since any skilled 15 mechanic could secure them in proper locations by moving the support to various limiting positions while the saws are idle and installing the stops for these limiting positions.

Although a matter of duplication, in case the pin 88 and auxiliary border templet are considered too light for 20 full assurance against interference and the arm stops are not provided, a heavier pin could be secured to the arm 90 at another location and a heavier border confining templet secured to the main frame to confine it. This would in no way hinder the action of the tracing pin 88 in following 25 the main templet 83.

In operation, after a workpiece or slab of material is clamped in the cradle, the operator grasps the handle 92 and brings the tracing pin 88 down out of the notch 95 and against the upper end of the templet 83. FIG. 6 shows the 30 path of movement of the tracing pin around the templet, while FIG. 5 shows a part of the path cut by each saw as controlled by the movement of the pin along the periphery of the templet. The cradle or holder is brought back to bottom position with the saws positioned in the channels 35 after each sawing operation.

FIGS. 10-12 show how the weights balance the work load statically and dynamically as the cradle and workpiece locations are shifted, the views particularly showing the dynamic balancing action wherein the weight 72 40 acts at longer or shorter effective fulcrum arm lengths correspondingly as the cradle acts at longer or shorter effective fulcrum arm lengths. This results from the reversal of movement directions through the compensating parallelogram 75, 79, 80, 58 (lower) described above.

45 FIG. 14 shows in perspective the long form which is cut out, and the broken lines show how this long article may be cut transversely to form as many small items of identical shape as desired, the number of items depending on the thickness of cut.

FIGS. 15 and 16 show a modified templet 83' which 50 has inner and outer elements providing a groove 96 between the mfor a tracer pin (not shown). The field limiting border templet is not needed in this case but if such a duplicate field limiting means as described is present, it will not interfere with the action of the pin with 55 the form templet since all movements along the form templet must necessarily be within the limiting field of action.

It is thus seen that the invention provides simple, 60 accurate and easily operated means for cutting forms by wire cutting devices. The saw strands of the machine described run horizontally but the organization and relationship of parts are such that other oriented dispositions could be used.

65 While certain embodiments of the invention have been described for purposes of illustration it is to be understood that there may be various embodiments and modifications within the general scope of the invention.

I claim:
70 1. Cutting apparatus comprising, in combination, a plurality of band cutting members each having an upper cutting strand spaced apart laterally, a workpiece holder for supporting a workpiece having upper and lower workpiece holding elements located above and below said 75 upper cutting strands, swing support means for said holder

providing vertical and horizontal movement of said workpiece holder relative to said upper cutting strands, templet means having a peripheral outline defining a predetermined pattern, a follower carried by said workpiece holder adapted to be guided along the peripheral outline of said templet means thereby to cause the cutting strands to engage the workpiece in adjacent cutting zones to form therein a design conforming to the peripheral outline of said templet means, and limit means in the form of a member having an inner edge spaced from and of a different configuration than said peripheral outline of said templet means operable to confine movement of said follower to thereby prevent a cutting strand in one cutting zone from entering a cutting zone of an adjacent cutting strand.

2. Cutting apparatus as claimed in claim 1 wherein said limit means member is of rectangular form surround-

ing said templet for limiting the outer range of movement of said holder.

3. Cutting apparatus as claimed in claim 1 wherein said follower is a tracing pin and including a notch in the inner edge of said limit means member to receive said tracing pin when the cutting apparatus is not in use.
